UNITED STATES PATENT OFFICE

137,938

DESIGN FOR AN AIRPLANE

Othmar F. Maycen, New York, N. Y.

Application June 16, 1943, Serial No. 110,467

Term of patent 7 years

(Cl. D71—1)

To all whom it may concern:

Be it known that I, Othmar F. Maycen, a citizen of the United States, residing in the Borough and county of Bronx, city and State of New York, have invented a new, original, and ornamental Design for an Airplane, of which the following is a specification, reference being had to the accompanying drawings, forming a part thereof, in which

Figure 1 is a top plan view of an airplane showing my new design;

Figure 2 is a front elevational view of the said airplane design;

Figure 3 is a side elevational view of the said airplane design; and

Figure 4 is a perspective view of said airplane design.

The characteristic feature of the present design resides in the motor units in their relation to, or association with the airplane wings.

I claim:

The ornamental design for an airplane, substantially as shown and described.

OTHMAR F. MAYCEN.
